DETACHABLE WHEEL CHAIR WALKING APPARATUS

Jean D. Thomas, Buffalo, N. Y.

Application July 13, 1949, Serial No. 104,401

4 Claims. (Cl. 155—22)

1

This invention relates generally to certain new and useful improvements in apparatus for use by invalids but more particularly to an apparatus for use in conjunction with or without a wheel chair to enable the user, supported by such apparatus, to walk and move about at will and thereby exercise his leg muscles to strengthen and improve their condition.

It has for one of its objects to provide an invalid walking apparatus of this character which is so designed and constructed as to be readily attached to and detached from a wheel chair, by the invalid himself, while seated in such chair, and which affords him complete safety and protection at all times when in use.

Another object of the invention is to provide the wheel chair walker with a novel two-part seat structure which can be readily folded out of use when desired.

Other features of the invention reside in the construction and arrangement of parts herein-after described and particularly pointed out in the appended claims.

In the accompanying drawings—

Figure 1 is a perspective view of my apparatus attached for use to a wheel chair. Figure 2 is an enlarged fragmentary section taken on line 2—2, Figure 1. Figure 3 is a fragmentary perspective view of the walker equipped with my improved seat. Figure 4 is an enlarged fragmentary section taken on line 4—4, Figure 3. Figure 5 is a cross section taken on line 5—5, Figure 4.

Similar characters of reference indicate corresponding parts throughout the several views.

By way of example, I have shown my invention in conjunction with a wheel chair of ordinary construction, 10 indicating the frame, 11 the seat, 12 the side arms, 13 the hand-propelled wheels, and 14 the casters or steering wheels. The walking device, indicated generally by the numeral 15, is adapted to be detachably connected in correlation to the wheel chair to permit the patient to transfer himself from the chair to the walker and vice versa with complete support at all times.

In its preferred construction, the walking device 15 consists of a comparatively light frame made of tubular material and including laterally-spaced side sections 16, 16 of substantially rectangular shape having handle bars 17, 17 at their upper ends. These handle bars are telescopically fitted in the companion side sections for vertical adjustment to accommodate the height of the patient for supporting himself while walking or exercising. At their lower ends these frame-sections 16 have casters 18 mounted thereon

which glidingly support the device when coupled with the wheel chair or at such times when the patient desires to use the device as a unit separate and detached from the wheel chair.

These frame-sections 16 are adjustably joined transversely in spaced relation at their front ends to accommodate the width of the wheel chair, while between their rear ends they are unobstructed to permit the patient to transfer himself from the chair to a walking position between such sections and back again. For this purpose these sections may be joined by telescopically-fitted guard rails or tie members 19, 20 and clamping screws 21 or the like provided for retaining them in their properly spaced position.

The rear end of the walking device is adapted to be detachably connected to the wheel chair and for this purpose its frame-sections have horizontal rearwardly-extending coupling members or bars 22 of tubular material adapted for disposition along opposite sides of the chair beneath the arm rests thereof, each member being fitted at one end with a coupling plug 23 for connecting it endwise by an axially-disposed bolt 24 to the

adjoining side section 15, the latter having a vertical row of bolt-receiving openings 25 therein to position the companion coupling member at the proper height in relation to the wheel chair. Connected to each coupling member 22 is a transverse hook-like fitting 26 whose threaded shank

27 is adjustably positioned in one or another of a series of openings 28 formed in such member to bring the hook portion of such fitting into embraced relation with the adjoining front portion of the chair-frame 10 in the manner shown in Figures 1 and 2. A nut or adjusting knob 29 is applied to the fitting-shank for detachably clamping the fitting securely in place, the latter having a rubber gripping sleeve 30 thereon. By this construction, the patient himself can readily attach and detach the walking device to his wheel chair while seated therein and without the aid of others, and it does not interfere or in any way prevent the wheel chair being propelled in its usual manner should the patient have occasion to do so.

Adjustably mounted at the rear side of the walker between its frame-sections 16 is a seat for the purpose of enabling the patient to assume a sitting posture when using the walker. This seat is vertically foldable to and from an operative position and consists of companion sections 31, 31, each secured at its outer end to a bracket 32 pivoted at 33 to the adjoining upright portion of the frame-section 16 of the

walker. The sections 31 are secured to the bracket 32 by a pair of clamps 34, 34 which are adjustably positioned to hold the sections 31 in a vertical position when the sections 31 are in an operative position. The sections 31 are secured to the bracket 32 by a pair of clamps 34, 34 which are adjustably positioned to hold the sections 31 in a vertical position when the sections 31 are in an operative position.

walker. Each bracket includes a channel portion 34, rising above its pivot, which embraces the frame-section in the operative position of the seat, as shown in Figure 3, and effectually retains the same in a horizontal position, the opposing inner ends of the seat-sections 31 substantially meeting and abutting each other as shown. As shown in Figure 4, one seat-section has an eye 35 on the underside of its inner end and the companion seat-section has a mating hook 36 thereon, whereby such sections are coupled against accidental displacement.

While manifestly simple, compact and inexpensive in construction, this wheel chair walker or exerciser attachment is very practical and enables the patient himself to connect it to and disconnect it from his wheel chair and to have maximum confidence for support and complete safety and protection when he desires to exercise his leg muscles and at the same time be assured that at the end of such exercising period he can again relax in his chair by merely changing from a standing to a sitting posture. In practice, the patient propels his wheel chair to the walking attachment and after connecting the parts, he is in unobstructed correlation with the attachment to transfer himself unaided from the chair to a standing posture between the frame-sections 16, 16 and, after exercising, as readily transfer himself to the chair, and with the assurance of complete supporting protection at all times.

I claim as my invention:

1. A walking device for detachable connection to a wheel chair, comprising a wheeled frame having members projecting from the rear end thereof for disposition along opposite sides of the chair, and clamping elements applied transversely of said members for releasable clamping engagement with adjoining portions of the wheel chair.

2. A walking device for detachable connection to a wheel chair, comprising a wheeled frame having members projecting from the rear end thereof for disposition along opposite sides of the chair, and hook-like fittings adjustable transversely on said members for clamping engagement with the adjoining portions of the wheel chair.

3. A walking device for detachable connection to a wheel chair, comprising a wheeled frame having members projecting from the rear end thereof for disposition along opposite sides of the chair, and fittings applied to said members for detachably clamping adjoining portions of the wheel chair thereto, each of said fittings including an attaching shank engageable transversely with the companion member and provided at one end with a hook between which and such member the adjoining portion of the wheel chair is adapted to be detachably clamped.

4. A walking device for detachable connection to a wheel chair, comprising a wheeled frame having members projecting from the rear end thereof for disposition along opposite sides of the chair and having rows of transverse openings therein, and fittings engageable with one or another of the openings in said members for detachably clamping adjoining portions of the wheel chair thereto, each of said fittings including an attaching shank having a nut at one end and a hook at its other end.

JEAN D. THOMAS.
